UNITED STATES PATENT OFFICE.

JULES HECTOR HIRT, OF EL PASO, TEXAS.

CAUSTIC-SODA PROCESS.

1,152,949.

Specification of Letters Patent. Patented Sept. 7, 1915.

No Drawing.

Application filed February 11, 1913. Serial No. 747,607.

To all whom it may concern:

Be it known that I, JULES HECTOR HIRT, a citizen of the United States, residing at El Paso, in the county of El Paso and State 5 of Texas, have invented certain new and useful Improvements in Caustic-Soda Processes, of which the following is a specification.

This invention relates to a caustic-soda 10 process and product, and its object is to produce caustic soda (2NaOH) at low cost.

In carrying out my new process, I take approximately anhydrous sodium sulfate (Na_2SO_4) and mix it with about one-half 15 its weight of saw-dust, either wet or dry, and charge the hot end (near the fire bridge) of a reverberatory tank-furnace, preferably continuously, with the mixture.

Under the furnace heat, the sodium sulfide 20 melts at a temperature of 880°C . and immediately begins to be reduced by destructive distillation of the saw-dust, to sodium sulfid, in consequence of the combined action of volatile, heavy hydrocarbons 25 in the saw-dust and of the extremely porous charcoal into which the saw-dust is converted by the destructive distillation of it.

The sodium sulfid produced, fuses at a 30 temperature of about 600°C ., and in consequence the bath of sodium sulfid is extremely mobile, having a consistency about that of milk. In this freely fluid state it can be readily tapped from the furnace tank at the cool end. This freely-flowing sodium-

35 sulfid product of the furnace is partially protected from oxidation in air by the soot which is disseminated through the bath, the soot resulting from the destructive distillation of the saw-dust. And while in the 40 furnace, the saw-dust floats on top of the sodium-sulfid bath and there protects the bath from oxidizing action by the flame.

An advantage of using the saw-dust is 45 that the hydrocarbons released in the destructive distillation of the saw-dust effect a very rapid reduction of the sodium sulfate to sodium sulfid and produce most of the soot which protects the molten sulfid from oxidation. The importance of protecting 50 the molten sulfid from oxidation is that if it be not so protected when tapped out in its liquid form from the furnace, it will burst spontaneously into flame and thereby will revert, or will tend to revert, back into 55 sodium sulfate.

The saw-dust floating on the bath consti-

tutes a covering of more or less depth, and which is exposed directly to the reverberatory-furnace flame and heat. The temperature of the bath is necessarily higher than 60 the temperature of the saw-dust, and the bath boils up through the saw-dust covering while the saw-dust is undergoing the destructive distillation, so that the oxidation-resistant soot is well distributed throughout 65 the molten sulfid.

As saw-dust contains only about one-third of one per cent. of ash, its use results in a purer product than would be obtained if coal or coke, which contain about ten per 70 cent. of ash, were used in lieu of the saw-dust.

In the production of caustic soda (2NaOH), or sodium hydrate, the sodium sulfid in its freely fluid state is tapped from 75 the furnace into, and is cooled in, water contained in vats and in which water the sodium sulfid is soluble.

In the vat or vats, hot or cold milk of lime or calcium hydrate ($\text{Ca}(\text{OH})_2$) in dilute solution is added, and the liquor in each successive vat becomes more and more caustic, the sodium sulfid becoming converted into caustic soda in accordance with the formula 80

The calcium sulfid is insoluble in water in the presence of calcium hydrate, and precipitates. 90

While hot milk of lime can be added to an aqueous solution of sodium sulfid in excess of the quantity which is required to effect the reaction, yet only a portion of the sodium sulfid will in that case be converted into sodium hydrate or caustic soda for in the vats the particles of calcium hydrate become coated with insoluble calcium sulfid, and such coating interferes with the conversion of the sodium sulfid into sodium hydrate. Thus if milk of lime were added to any vat in large excess, or otherwise than in diluted solution, the reaction would be in accordance with the above formula, but incomplete. 95

Under the foregoing condition only a small portion of the sodium sulfid would be converted into caustic soda. On the other hand, by adding the milk of lime to the contents of the vat or vats in successive small portions, the reaction proceeds with rapidity and completeness in the production of 100 105 110

caustic soda solution, which is afterward treated in a known manner to refine it.

What I claim is:

1. The process of making caustic soda consisting in flowing molten sulfid of soda into water and thereby dissolving the sulfid and adding thereto while hot, successive small portions of calcium hydrate in dilute solution.
- 10 2. The process of making caustic soda

consisting in flowing molten sulfid of sodium into water and thereby dissolving the sulfid and in adding to the hot solution, calcium hydrate.

In testimony whereof I affix my signature 15 in presence of two witnesses.

JULES HECTOR HIRT.

Witnesses:

G. BLAKE,

EDWARD E. BLACK.
